UNITED STATES PATENT OFFICE

GEORGE E. PICKUP, OF NEWARK, OHIO, ASSIGNOR TO THE WEHRLE COMPANY, OF NEWARK, OHIO, A CORPORATION OF OHIO

DOOR-COUNTERBALANCING MEANS

Application filed June 21, 1928. Serial No. 287,061.

The invention relates to improvements in counterbalancing means for stove doors and the like.

Difficulty has been experienced with counterbalancing means as applied to doors of present manufacture because of the proximity of the actuating springs to the source of heat within the stove or oven with attendant loss of temper. It is likewise common practice to locate the counterbalancing means within the side walls of the oven structure, thus rendering its several members inaccessible for repair or replacement and complicating assembly operations, with a resultant increase in manufacturing cost.

One object of the invention is to provide a novel arrangement of the parts of a door counterbalancing means in an oven structure permitting of the location of the spring actuating members remotely from the source of heat thus obviating the possibility of deterioration from continued exposure to the oven heat.

Another object of this invention is to provide a new and improved counterbalancing device for the oven doors, all parts of which are of simple and inexpensive construction and adapted to be completely assembled together with the doors on the door frame prior to mounting of the door frame on the oven structure.

Still another object of the invention is to provide a torsion spring counterbalancing means for oven doors having operating arms which move in a plane close to the plane of the door frame and substantially parallel therewith.

Further objects and advantages of the invention will be understood from the following detailed description taken in connection with the accompanying drawing in which:

Figure 1 is a rear elevation of a door frame of an oven structure having doors counterbalanced in accordance with the present invention.

Fig. 2 is a side view of the oven shown in Fig. 1 with one side cut away to show the door hinges in section.

Fig. 3 is a plan view of the frame shown in Fig. 1.

While I have shown in the drawings and will herein describe one embodiment of my invention for the purposes of illustration, I do not intend to be limited thereby to the form disclosed but aim to cover all modifications and alternative constructions falling within the scope of the invention as expressed in the appended claims.

As illustrated herein, the invention is embodied in an oven having a front frame with side members 5, top and bottom members 6 and 7 and an intermediate cross bar 8 connecting the side members and co-operating respectively with the top and bottom members to define top and bottom door openings. These upper and lower openings afford access to the so-called baking and broiling oven spaces which are usually heated by one or more elongated burners shown at 8^a, placed behind the door frame approximately at the level of the frame member 8, the heat being directed upwardly to the baking oven and downwardly to the broiling oven.

The openings are adapted to be closed by doors 9 having pins 10 projecting laterally from their side edges near the bottom thereof and pivotally supported in the side members 5 so that the doors will abut against the front faces of the frame around the door openings when the doors are in closed positions as shown in the drawings.

To retain the doors in closed position and to yieldingly resist swinging thereof to open position, a counterbalancing means is provided, which, in its preferred form, comprises independent resilient means mounted on the door frame a substantial distance from the source of heat within the ovens, and operably connected to the respective doors eccentrically of the axes of their pivot pins 10.

Thus it is possible to completely assemble all of its operating parts on the door frame prior to the mounting of the latter on the oven proper. Also the springs for both of the doors are located remotely from the source of oven heat. This simple and inexpensive arrangement is made possible by utilizing the effort of a coiled spring in torsion with its actuating arm movable substantially in the plane of the door frame and connected by 100

a tension link to the door counterbalanced thereby.

In accordance with my invention, each resilient means comprises a coiled spring, the spring which counterbalances the upper door being represented at 11 in Fig. 1 and mounted with its axis perpendicular to the plane of the door, as for example, upon a stud 12 secured to and projecting rearwardly from the lower frame member 7. The ends of the spring form arms 13 and 14 extending at substantially right angles to its axis. The arm 13 extends inwardly along the lower frame member 7 and is held against movement by a stationary lug 15. The arm 14 projects outwardly in opposite direction along the frame member 7 terminating at a point substantially in vertical alignment with the vertical side edge of the lower door opening. Accordingly, a suitable tensile member in the form of a link 16 is employed to operatively connect the movable arm 14 of the spring 11 with the upper door. The link 16 is formed with a loop at its lower end which is received in a hook 18 formed at the outer end of the movable spring arm 14.

The link 16 extends vertically along the side member 5 to avoid interference with the lower door opening 9 and is connected to the upper door eccentrically of its axis through the medium of a crank arm 19 preferably formed integral with the side edge of the door and projecting inwardly therefrom through a slot 20 in the side member 5 of the frame. Near its extremity the arm 19 is formed with a hole for receiving the hooked upper end of the link 16. A shoulder 21 may be formed on the arm 20 for engagement with the rear surface of the frame member 5 to limit the opening of the door to a horizontal position.

A similar spring 11^a mounted on the opposite adjacent end of frame member 7 is utilized to counterbalance the lower door. In this instance such a spring has its inwardly extending arm 13^a secured against movement by a lug 15^a. An arm 14^a extends outwardly along the frame member 7, terminating at a point substantially in vertical alignment with the adjacent vertical side edge of the lower door. This arm 14^a is connected to the lower door by means of a relatively short link 17^a which is formed with a loop in its lower end engaging the hook 18^a on the outer end of the arm 14^a. A hook on its upper end is received in a hole near the extremity of an eccentric arm 19^a similar to that employed on the upper door.

I claim as my invention:

1. In a stove front having a frame comprising top, bottom and side members defining a door opening, the combination of a door pivotally supported on said frame and counterbalancing means for said door comprising a coiled torsion spring mounted on said bottom member below said opening with

its axis disposed substantially perpendicular to the plane of said frame, one end of said spring being secured against rotation, the other end projecting laterally of the frame beyond one vertical side edge of the door opening, a link operatively connected to the free end of said movable arm and extending upwardly along one of said side members, and means connecting said link to said door eccentrically of the axis thereof for applying the force of said spring to counterbalance said door.

2. An oven structure having, in combination, a frame comprising top, bottom and side members with an intermediate cross bar defining the door openings of upper and lower oven spaces, the heating unit for said spaces being disposed substantially opposite said cross bar, doors for closing said openings pivotally supported on said frame, and independent counterbalancing means for said doors comprising torsion springs mounted on opposite sides of said frame substantially below the lower opening and having anchored arms extending inwardly along said lower member and movable arms extending outwardly along said lower member, and means extending along one side edge of the lower door opening and connecting the movable arm of one spring with the upper door to counterbalance the same, and means for applying the force of the other spring to counterbalance the lower door.

3. An oven structure having, in combination, a front frame defining door openings for upper and lower oven spaces heated respectively from below and from above by a common burner unit, a pair of doors each for closing one of said openings, and a pair of torsion springs mounted on opposite sides of said frame a substantial distance below said unit, means for applying the force of one of said springs to counterbalance said upper door, and means for applying the force of said other spring to counterbalance said lower door.

4. The combination with a frame defining an oven opening, of a door pivotally supported by said frame for closing said opening, and counterbalancing means therefor comprising a torsion spring mounted on said frame and having one end anchored and the other end movable in a plane substantially parallel to the door opening, and means connecting said movable end to said door for urging said door toward closed position.

5. The combination with a frame defining an oven opening, of a door pivotally supported on said frame for closing said opening and counterbalancing means therefor comprising a coiled torsion spring mounted on said frame with its axis substantially perpendicular to the plane thereof, means acting on one end of the spring to prevent rotation thereof, and means operatively connect-

ing the other end of said spring to said door for applying the force of said spring to swing said door toward closed position.

6. In a stove front having a frame defining an oven opening, the combination of a door for closing said opening and counterbalancing means therefor, comprising a torsion spring mounted on one side of said frame below said opening and having a vertically movable actuating arm, and a link connecting said arm to said door for applying the force of said spring to urge said door to closed position.

7. The combination with a frame defining an oven opening, of a door pivotally supported by said frame for closing said opening, and counterbalancing means therefor comprising a torsion spring mounted on said frame with its axis perpendicular to the plane thereof and having one end anchored, the other end movable in a plane substantially parallel to the door opening, and means connecting said movable end to said door to swing said door toward closed position.

25 In testimony whereof, I have hereunto affixed my signature.

GEORGE E. PICKUP.
